KNITTED SHIRT OR SIMILAR ARTICLE

Meyer Geist, New York, N. Y.

Application February 27, 1956, Serial No. 40,360

Term of patent 14 years

(Cl. D3—25)

Fig. 1

Fig. 2

Fig. 3

Fig. 4

Fig. 1 is a front view of a knitted shirt or similar article, showing my new design.

Fig. 2 is a rear view thereof.

Fig. 3 is a fragmentary front view of the item as shown in Fig. 1 with collar portion in raised position and the tie portion closed.

Fig. 4 is a fragmentary front view of the blouse shown in Fig. 1 with the collar raised and the points fastened together to form a hood.

I claim:

The ornamental design for a knitted shirt or similar article, substantially as shown.
